UNITED STATES PATENT OFFICE

2,535,724

MINIATURE BOWLING ALLEY

Joseph A. Crowley, North Arlington, N. J., assignor to Clover, Incorporated, Jersey City, N. J., a corporation of New Jersey

Application January 27, 1947, Serial No. 724,685

2 Claims. (Cl. 273—39)

1

This invention relates to novel and useful improvements in games particularly those simulating standard size bowling alleys.

The main purpose of this invention is to provide a device conducive of pleasure and enjoyment to people in all walks of life and particularly those interested in bowling.

A further object of this invention is to provide means for receiving and directing a simulated bowling ball in the general direction of miniature pins.

A further object of this invention is to provide novel and improved baffle or guide means for elevating said simulated bowling ball.

Another object of this invention is to provide an improved back-stop means adapted to restrict the travel of said ball and of said pins.

A further object of this invention is to provide a track means adjacent the edge or end of said pin and ball travel and the alley floor.

Other objects and features of novelty as well as those mentioned hereinabove, will become apparent to those skilled in the art, in following the description of the preferred embodiments of the instant invention illustrated in the accompanying drawings, wherein:

Figure 1 is a longitudinal sectional view of the preferred embodiment of the instant invention showing the travel of a plurality of bowling balls therein;

Figure 2 is a broken plan view of the invention disclosed in Figure 1;

Figure 3 is a transverse sectional view of the invention disclosed in Figure 1 and taken substantially on the line 3—3 of Figure 1 and in the direction of the arrows;

Figure 4 is a fragmentary sectional view of a detail of construction shown in Figure 1 and taken substantially on the line 4—4 thereof and in the direction of the arrows;

Figure 5 is a perspective view of the invention disclosed in Figure 1, and

Figure 6 is a diagrammatic view of a second embodiment of the instant invention.

Referring now in detail to the illustrated preferred embodiment of the instant invention, like reference characters are used throughout to indicate similar elements.

A substantially rectangular housing 10 is composed of any suitable material such as metal, paper products, wood and the like and is generally indicated by the reference numeral 10. An aperture 12 is provided in the front wall 14 of said housing and is adapted to receive simulated bowling balls 16 therein. The said bowling balls

may be thrown or otherwise projected through said aperture 12. It is noted that the lower portion 18 of the said wall 14 is in-curved forming a funnel-like entrance for the said bowling balls. A suitable clamp 20 may be secured to the in-curved portion 18 for securing the said in-curved portion securely to the walls 22 and 24 of the said housing 10. A ramp 26 is provided as an extension of the base 28 of said housing. It is noted from an inspection of Figures 1 and 5 that the said ramp extends outwardly of said housing and has a bevelled portion 30 at the end thereof. It is apparent that the invention may be placed on a table, floor or some other suitable stand, the ball rolled on said table climbing said bevelled portion and continuing up the ramp 26. Secured to the said base and wall 14 is an S-shaped baffle means or chute generally indicated at 32. The said chute 32 is composed of two baffles 34 and 36. The said baffle 36 is arcuate and has one end thereof secured by some suitable means to the base 28. Baffle 36 as well as the baffle 34 is simply a simple plate of a suitable material having the desired configuration. The second baffle 34 is somewhat similar to the said baffle 36 and is disposed partially thereover and assumes a similar configuration. It is noted that when the baffles are viewed as a unit they assume the general shape of an S with the larger arcuate portion on the bottom and the smaller arcuate portion at the top thereof. It is readily apparent from an inspection of Figure 1 that the bowling balls 16 will issue from the end of the said chute in substantially the same general direction as they are received in said chute. Further, it is noted that upon issuing from the chute the balls are elevated with respect to the entrance position.

Adjacent the entrance point of the baffle 36 is a pair of guides 38 and 40 which receive and direct the bowling balls to said baffle from the said ramp 26.

Suitable sides 42 and 44 assuming the same general shape as the chute are provided at the marginal edges of said chute and are adapted to restrict and retain the bowling balls therein. The sides 42 and 44 may be omitted and the side walls 22 and 24 used as the restricting means. It is further noted that the base portion 28 may be omitted if so desired, since this member is used simply to close the housing thereby forming a substantially closed structure.

If so desired, a portion 48 may be secured to the sides 42 and 44 thereby forming a guide plate. It is noted that this guide plate 48 is provided

to retain bowling balls 16 in the prescribed course if they are not started with sufficient initial force to complete the entire circuit.

Reinforcing members 50 and 52 are provided on the back wall 54 in order to lend rigidity to the housing. A step 56 is provided transversely of said housing 10 and rests on the said support 52. A strip 58 is provided at the upper portion of said back wall 54 and has an upholstered back-stop swingably mounted therefrom. The said back-stop, indicated at 60, may be mounted by any conventional swinging means such as the screws and eyes generally indicated at 62. A reinforcing strip or block 64 is secured adjacent the said step 56 and may be received in the said side walls 22 and 24. This block forms a bearing surface for the terminal or end portion of a simulated bowling alley floor 66. Gutters 68 are provided adjacent the edges of the said floor 66 simulating the gutters of a conventional full-scale bowling alley. It is noted that by the construction of the step 56 a trap is provided adjacent the terminal portion of the said floor 66 which is quite similar to the trap at the terminal portion of a conventional full size bowling alley. Pins 70 are provided in the usual manner at the said terminal portion of the said alley 66 and are obviously adapted to be struck by the balls 16 in the operation of the game. It is noted that the sides 22 and 24 have upwardly extending ends 72 simulating the protector plates found between conventional full scale bowling alleys.

The operation of the invention is deemed quite obvious. A ball 16 is thrown into the aperture 12, being elevated on the ramp 26 and is guided into the chute 32 by means of the said guides 38 and 40. After taking an S-turn and being elevated to the floor 66, the ball then strikes certain of the pins or rides down either of the gutters 68. Thereupon, the ball and pins (if any are struck) are limited in travel by striking the swingingly mounted back-stop 60. The balls and pins are retained in the trap defined by the step 56 co-operating with a portion of the back wall 54 and the sides of the housing along with the stepped portion 64. It is noted that by this preferred construction, the operator may view the travel of his bowling ball from the back end thereof just as a bowler does in a full scale bowling alley.

Referring now to Figure 6, a second embodiment of the present inventive concept is disclosed. A suitable housing generally indicated at 80, is provided quite similar to the housing 10. An aperture 82 is provided in the front wall thereof

adapted to receive balls 16 therein which ride up an inclined ramp 84. A suitable chute 86 is provided near the uppermost portion of the said ramp and is adapted to receive the balls 16 and direct them to the floor 88. The said chute 86 has a hairpin turn therein and is adapted to direct the balls substantially in a direction opposite to the entrance direction. Pins may be provided at the terminal portion of said floor 88 and a suitable trap 90 similar to the trap defined at 56, may be provided therein. The swinging back-stop may be utilized in this second embodiment of the instant invention if so desired.

Having thus defined the instant invention what is claimed as novel and improved is as follows:

1. A miniature bowling alley comprising a housing having front and back walls, said front wall having an opening therein at the bottom thereof, a ramp forming a portion of the base of the housing and projecting through said opening, a substantially S-shaped chute having an inlet portion communicating with said ramp, the inlet portion of said chute being partially opened, a top on a portion of said chute, said chute having an outlet, a top in said housing forming a bowling alley floor and having ends, the first end of said floor being positioned adjacent the chute outlet, the opposite end of said floor terminating adjacent but spaced from the housing back wall, a back stop swingingly mounted at its upper end to said last mentioned wall, a trap connecting said last mentioned wall and the same end of said floor.

2. The combination of claim 1 and said S-shaped chute having its lower arcuate portion of a relatively larger radius than its upper arcuate portion.

JOSEPH A. CROWLEY.
